UNITED STATES PATENT OFFICE.

GEORGE R. FARRELL, OF LEOMINSTER, MASSACHUSETTS, ASSIGNOR TO HARVARD NOVELTY COMPANY, OF LEOMINSTER, MASSACHUSETTS, A CORPORATION OF MASSACHUSETTS.

DESIGN FOR A BARRETTE OR HAIR-FASTENER.

No. 39,554.

Specification for Design.

Patented Sept. 22, 1908.

Application filed June 9, 1908. Serial No. 437,600. Term of patent 3½ years.

To all whom it may concern:

Be it known that I, GEORGE R. FARRELL, a citizen of the United States, residing at Leominster, in the county of Worcester and State of Massachusetts, have invented a new, original, and ornamental Design for Barrettes or Hair-Fasteners, of which the following is a specification, reference being had to the accompanying drawing, forming part thereof.

The drawing is a perspective view of a barrette or hair fastener, showing my new design.

I claim:

The ornamental design for a barrette, or hair fastener, as shown.

GEORGE R. FARRELL.
